UNITED STATES PATENT OFFICE.

PAUL WERNER SEEWER, OF LONDON, ENGLAND. ASSIGNOR TO THE ENGLISH ELECTRIC COMPANY, LIMITED, OF LONDON, ENGLAND, A BRITISH COMPANY.

HYDRAULIC TURBINE.

Application filed June 6, 1927, Serial No. 196,952, and in Great Britain June 18, 1926.

Where it is desired to shut down a hydraulic reaction turbine particularly when coupled to an electric generator it is necessary to provide some means of absorbing 5 quickly the energy stored in the rotating masses in order that they may be brought to rest within a short time. With this in view it has been the practice to provide mechanical brakes to be applied to rotating surfaces and produce the absorption of the 10 energy by solid friction. In accordance with the present invention a hydraulic brake is provided. This is done by projecting free jets of water against the blading of the runner of a reaction turbine in such a direction or directions as to produce on the runner impulses which oppose its rotation in the normal running direction. These jets can be brought into action on the outlet side of the 15 runner and may be directed towards the runner either axially or transversely. The former arrangement is particularly suitable in the case where the draught tube is bent as is commonly the case with turbines which 20 have the shaft horizontal. Transversely directed jets can be conveniently used with any form of draught tube since they can be projected from the side wall of this tube a short distance away from the outlet surfaces of 25 the runner.

The preferable arrangement of the axial jets is that in which a single jet is used 30 mounted in the bend of the draught tube at a point directly in line with the axis of the runner. The jet will then strike on the end 35 of the runner which will have a conical centre by which the jet will be deflected laterally. The deflected jet encounters the back surfaces of the blades which are so 40 formed that the pressure of the jets upon them will produce a tangential component opposing rotation in the normal running direction.

Where transversely directed jets are employed they are preferably arranged in the 45 wall of the draught tube or adjacent parts of the turbine structure just outside the outlet end of the runner. In this case it may 50 probably be more advantageous to use several jets than a single jet, each jet being in a direction which is to a large degree transverse but also contains an axial component so as to cause it to enter the spaces surrounded by the outlet parts of the runner 55 vanes and to pass across the runner centre

(preferably without encountering it to any extent) and then impinge upon the backs of the vanes as near as may be desired to those parts of the outlet edges where the vanes adjoin the centre of the runner. By this means the jets are caused to exert impulses 60 on the vanes which have tangential components which oppose the normal direction of rotation.

The jets may be formed as outlets from an annular channel arranged in the lower end 65 of the speed ring or other convenient position, and can be normally closed by some form of stop valves, for instance, flaps each of which is thrown open by the action of the 70 jet when it is being brought into action.

The jets are supplied with water preferably from a point in the pipe line above the main valve which controls the turbine supply, or from some other source of supply 75 and can be brought into action automatically or otherwise by opening a valve in the connecting pipe. It will be understood that the valve will only be brought into action after the runner casing and draught tube have 80 been emptied of water.

In addition to the impulse action previously described, the hydraulic braking action will also be brought about to a certain extent by the pumping action of the runner 85 employing that part of the water from the jet which enters the spaces between the vanes and is retained there owing to centrifugal action due to the rotation of the runner.

Two embodiments of the invention will 90 now be described by way of example with reference to the accompanying drawings of which Figure 1 shows a sectional elevation on the line I—I of Figure 2 the runner and a draught tube, and co-acting parts of a reaction turbine having a vertical shaft. Figure 2 shows a plan on the line II—II of Figure 1 which is the floor level of the turbine. Figure 3 shows a central sectional elevation 95 of a reaction turbine having a horizontal shaft.

Referring to Figures 1 and 2 the runner and its blades are denoted respectively by the numerals 1 and 2 and the former is attached in known manner to the lower end of a vertical shaft (not shown) which is attached at its upper end to the rotor of a dynamo electric machine (not shown) mounted upon a foundation indicated by the chain dotted lines 3. The arrangements of 105

these turbines are quite well known and the drawings therefore are only intended to show fully those parts which have a direct connection with the present invention. The 5 water is delivered to the blades 2 of the runner from a spiral casing (not shown) which is disposed around the runner 1 in known manner. The casing itself is supplied with water through the conduit pipe 4 which is 10 connected to a pipe line (not shown) through a main valve 14.

In accordance with the invention a free jet of water 13 is caused to strike the under side of the runner blades 2 in a suitable direction to supply the necessary braking effort. This jet is delivered from a nozzle denoted by the numerals 9 and 10 which is fixed to the wall of the upper circular part of the draught tube 6 so that it projects but 20 slightly into the water-way of this part. The nozzle is connected to a pipe 7 and the water is delivered through this pipe from the pipe-line side of the main valve 14 under the control of a hand operated sluice valve 8.

25 Before applying the hydraulic brake, the circular part of the draught tube 6 above the nozzle, must be emptied of water and this can be effected or assisted by means of a ventilating pipe 11, which upon opening the 30 valve 12, admits air at atmospheric pressure to the top of the draught tube 6. The sluice valve 8 can then be opened to start the jet 13 and bring about the braking effort.

The nozzle consists of a part 9 which is 35 fixed to the draught tube 6 and to the pipe 7, and a part 10 which is screwed to the part 9 so that it forms a removable mouthpiece provided with an internal circular bore suitably tapered and concentric with the axis 15 40 of the fixed part 9.

It may be advantageous to provide a second mouthpiece 10 interchangeable with the one above referred to and constructed so as to make it easily possible to determine 45 experimentally, after the parts 7 and 9 have been fixed in position, the precise direction in which the jet 13 should be applied to the blades 2 to obtain the best braking action. This second mouthpiece would be provided 50 with an internal circular bore suitably tapered and offset at a small angle to the axis 15, so that the jet 13 would be slightly deflected from the position shown in Figure 1 in a direction which could be altered according to the angular setting of the mouthpiece 10 upon the fixed part 9.

A shield 16 may be provided in the draught tube 6, beneath the nozzle 9, 10 where it projects into this tube, for the purpose of preserving a proper stream-line shape of the inside surface of the draught tube.

Referring to the turbine shown in Figure 3 the water is delivered in known manner into the spiral casing 18 and passes thence in a direction radially inwards across the blades 2 of the runner 1 mounted on a horizontal shaft overhung in bearings. The water on leaving the blades 2 passes out into the draught tube 6, the first part of which is 65 bent through ninety degrees from a horizontal to a vertical plane before it passes through the foundation. The jet 13 of water for braking is delivered from a nozzle 10 fixed in the bend of the draught tube 6 at a point directly in line with the axis of 70 the runner 1 and so that it strikes on the conical centre 17 of the runner which deflects it laterally on to the blades 2 upon which a comparatively steady braking thrust is produced. The upper part of the draught tube must of course be emptied of water before the hydraulic brake can be brought into 75 action.

What I claim as my invention and desire 80 to secure by Letters Patent is:—

1. A hydraulic turbine provided with a braking device comprising a runner of the re-action type, a chamber adapted to receive the water flowing out from the runner during normal operation, a nozzle adapted to discharge into said chamber, in the absence of the normal outflow of water from the runner, a free jet which impinges against the runner on the outflow side. 90

2. A hydraulic turbine provided with a braking device comprising a runner of the re-action type, a chamber adapted to receive the water flowing out from the runner during normal operation, a nozzle adapted to discharge through an aperture in the wall of said chamber during the absence of the normal outflow of water from the chamber 100 a free jet in a direction having a substantial axial component and impinging upon the runner on its outflow side, means for supplying water under pressure to said nozzle and means for controlling said supply. 105

3. A hydraulic turbine provided with a braking device comprising a runner of the re-action type, a chamber adapted to receive the water flowing out from the runner during normal working, said chamber being in the form of an elbow tube, said tube having an aperture substantially in line with the axis of the runner, a nozzle adapted to discharge through said aperture a jet of water against the runner when the normal flow of water has been cut off, means for supplying water under pressure to said nozzle and means for controlling said supply. 110

115 In testimony whereof, I affix my signature.

PAUL WERNER SEEWER.
